(57) **CLAIM**

The ornamental design for an eye exam apparatus, as shown and described.

DESCRIPTION

FIG. 1 depicts a front view of the eye exam apparatus of the invention, in which the eye examination apparatus is in a lowered position.

FIG. 2 depicts a front view of the eye exam apparatus of the invention, in which the eye examination apparatus is in a raised position.

FIG. 3 depicts a right side view of the eye exam apparatus of the invention, in which the eye examination apparatus is in a lowered position.

FIG. 4 depicts a right side view of the eye exam apparatus of the invention, in which the eye examination apparatus is in a raised position.

FIG. 5 depicts a left side view of the eye exam apparatus of the invention, in which the eye examination apparatus is in a lowered position.

FIG. 6 depicts a left side view of the eye exam apparatus of the invention, in which the eye examination apparatus is in a raised position.

FIG. 7 depicts a rear view of the eye exam apparatus of the invention, in which the eye examination apparatus is in a lowered position.

FIG. 8 depicts a rear view of the eye exam apparatus of the invention, in which the eye examination apparatus is in a raised position.

FIG. 9 depicts a perspective front view of the eye exam apparatus of the invention, in which the eye examination apparatus is in a lowered position.

FIG. 10 depicts a perspective front view of the eye exam apparatus of the invention, in which the eye examination apparatus is in a raised position.

FIG. 11 depicts a perspective rear view of the eye exam apparatus of the invention, in which the eye examination apparatus is in a raised position.

FIG. 12 depicts an enlarged view taken along FIGS. 1 and 2.

FIG. 13 depicts an enlarged view taken along FIGS. 1 and 2.

(Continued)

FIG. 14 depicts an enlarged view taken along FIGS. 3 and 4.

FIG. 15 depicts an enlarged view taken along FIGS. 3 and 4; and,

FIG. 16 depicts an enlarged view taken along FIGS. 5 and 6.

In the drawings, the broken lines are for the purpose of illustrating portions of the eye exam apparatus that forms no part of the claimed design.

1 Claim, 16 Drawing Sheets

Related U.S. Application Data

17, 2017, now Pat. No. 11,266,309, which is a continuation-in-part of application No. PCT/US2016/068410, filed on Dec. 22, 2016, which is a continuation of application No. 15/268,572, filed on Sep. 17, 2016, now abandoned.
